UNITED STATES PATENT OFFICE.

LEOPOLD ORWAN, OF NEW YORK, N. Y.

DESIGN FOR A PATTERN FOR MUFFLERS.

SPECIFICATION forming part of Design No. 32,717, dated May 22, 1900.

Application filed April 13, 1900. Serial No. 12,773. Term of patent 7 years.

To all whom it may concern:

Be it known that I, LEOPOLD ORWAN, a citizen of the United States, residing at New York, in the county of New York and State of New York, have invented and produced a new and useful Design for Patterns for Mufflers, of which the following is a specification.

The figure of the drawing is a plan view of my new design for a pattern for mufflers.

In said drawing the pattern is shown as having a series of perforated lines which serve as guides for the cutter. These perforated lines comprise the longitudinal ogee-curved lines 1 and the inclined-plane lines 2 at the smaller ends of each ogee curve. The chart or pattern has two ogee-curved lines, and a central longitudinal-plane line of perforations 3 divides each pair of pieces when cut on the per-

forated lines. A transverse line 4 divides the pattern centrally.

The leading or material feature of my design consists in the pattern having the longitudinal ogee lines 1 and the inclined-plane lines 2 at the smaller ends of each ogee curve.

Having thus fully described my invention, what I claim is—

The design for a pattern for mufflers, substantially as shown and described.

In testimony whereof I have hereunto set my hand in presence of two subscribing witnesses.

LEOPOLD ORWAN.
